WILLIAM JOHNSTON, OF CINCINNATI, OHIO.

Letters Patent No. 83,286, dated October 20, 1868.

IMPROVED WINDOW-BLIND.

The Schedule referred to in these Letters Patent and making part of the same.

To all whom it may concern:

Be it known that I, WILLIAM JOHNSTON, of Cincinnati, in the county of Hamilton, and State of Ohio, have invented certain new and useful Improvements in Venetian Shutters, &c.; and the following is declared to be a full, clear, and exact description thereof, reference being had to the accompanying drawings, which are made a part of this specification.

My invention relates to a novel and simple construction of slats, and mode of mounting the same in Venetian window-shutters, blinds, doors, and lower windows or openings, for the purpose of making the same burglar-proof.

It consists—

First, in the use of cylindrical rods of metal, (steel or wrought-iron preferred,) as the axles of said slats, said rods being extended entirely across the frame in which they are used, and firmly fastened at their ends in the material thereof.

Second, in the use of metallic slats, constructed with a tubular or hollow sphere in the centre, extending through longitudinally, and made to turn freely on the said rods.

Third, in the use of a soft metallic bushing, with an external annular flange inserted in the ends of the said slats, for the purpose of lessening their friction on the said rods, and holding them out of contact with the frame.

In the drawings—

Figure 1 represents an inside view, partly in section on the line $x-x$, fig. 2, of a shutter or blind illustrating my invention, the slats being shown in a partially-opened position.

Figure 2 is a vertical section in the planes indicated by the line $y-y$, fig. 1.

Figure 3 is an elevation illustrating a modification in the manner of turning the slats.

Figure 4 represents a vertical section at $y-y$, fig. 3.

Figure 5 is an elevation illustrating another modification.

Figure 6 represents a vertical section at $y-y$, fig. 5.

A represents a frame, of wood or other suitable material, which may be of any of the customary forms and dimensions.

B B are cylindrical rods or tubes, preferably of steel or wrought-iron, of a sufficient diameter to afford the requisite strength and rigidity.

These rods are secured in the frame A, when made of wood, by being driven into deep sockets, a, in either two parallel sides thereof, (for vertical or horizontal slats,) and form the axles on which the slats revolve.

C C are slats, preferably formed of sheet-metal or malleable iron, in the manner shown in fig. 2, being provided with a longitudinal tubular portion, c, for the reception of the rods B, on which they are mounted.

The tube c is of sufficiently greater diameter than the

rods B, to allow of an annular space being left around them, when in position, to adapt them to be thus supported; and they are provided at their ends with soft-metal bushings, D, which form the bearing-surfaces of the slats, relieving them, for the greater portion of their length, of friction, and obviating the necessity of perfect rotundity of surface, the absence of which might otherwise prevent their operation.

The bushings D have formed, on their outer ends, annular flanges or shoulders, d, which form washers to support the ends of the slats out of contact with the frame, and thus prevent friction at those points.

One or both of the edges of the slats C are provided with a wire, E, for the purpose of stiffening them, and one of said wires in each slot, in connection with a notch, e, which may be made at any preferred point in the length of the slat, forms a staple for the attachment of the adjusting-rod F, or other attachment for that purpose.

The rod F may be provided, for the reception of the wires E, with suitable eye-bolts or staples, f, or other customary contrivance.

It is also provided with notches, f' f', for the reception of the tubular portion, c, of the slats, when in their closed position.

a' a" are the customary notches or recesses, for the reception of the ends of the rod F, when the slats are in their extreme positions.

In the illustration given in figs. 3 and 4, the connecting-rod F is dispensed with, the simultaneous movement of the slats being effected by idle-pinions, p, gearing with toothed thimbles, d', which perform all the functions of the thimbles or bushings d, hereinbefore described.

In the modification represented in figs. 5 and 6, the idle-pinions, p, are dispensed with, and the turning of the slats effected by a vertically-sliding rack, r, gearing with the toothed thimbles d.

The handle or knob h, by which the rack r is moved, may form a nut, working upon a screw-stud on the rack r, and serving as a clamp to secure the rack in any position.

When the toothed thimbles d' and pinions p or racks r are used, they may be concealed within the window-casing, as illustrated in the drawings.

Figs. 3, 4, and 6 represent portions of the framing removed to expose these appliances.

The rods B, being firmly locked in the sides of the frame, serve, in addition to their primary function, to strengthen and brace it, thus obviating the necessity of the intermediate cross-pieces or battens customarily used, and adapting a blind or door to be provided with slats for its whole length, if desired, and all the slats in one tier to be connected and simultaneously operated, or connected and moved in smaller sections, if desired.

The material of which the separate parts of my shutter are composed, and also the precise form named for the separate parts, may be varied to suit the taste, and its surfaces be provided with any desired ornamentation.

It is also obvious, that although my invention is primarily intended to render the structures in which it is used burglar-proof, and at the same time afford the desirable means for regulating the admission of light, air, &c., some or all of the separate parts thereof may be used in blinds, &c., for openings which do not require to be guarded against burglarious attempts at entrance.

It is also obvious that a portion only of the slats of a blind or other structure may be provided with my improved slats, the other part having the ordinary stationary ones, when preferred, without departing from the invention.

I am aware that metallic pivots have before been used in blind-slats, but the peculiarity of my device

consists in employing stationary rods, which form a rigid connection between the stiles, and upon which the slats turn.

Having thus described my invention,

I claim as new, and desire to secure by Letters Patent—

1. The through cylindrical rod B, fixed rigidly in the stiles, as an axle for a slat in window-blinds, shutters, doors, and lower windows or openings to turn upon, substantially as herein described.

2. The metallic slat, when formed with a tubular or hollow spine, running longitudinally through the same, and made to turn on the said cylindrical rods.

3. The bushings D, when provided with the annular flange d, adapted to form a washer at the end of the slat, for the purpose specified.

WILLIAM JOHNSTON.
